UNITED STATES PATENT OFFICE.

MEYER NUTA, OF CHICAGO, ILLINOIS.

INTERNAL-COMBUSTION ENGINE.

1,406,886.

Specification of Letters Patent. Patented Feb. 14, 1922.

Application filed October 6, 1920. Serial No. 415,191.

To all whom it may concern:

Be it known that I, MEYER NUTA, a citizen of the United States, residing at Chicago, in the county of Cook and State of Illinois, have invented certain new and useful Improvements in Internal-Combustion Engines, of which the following is a specification.

My invention relates to internal combustion engines and has for its object to secure a very complete scavenging of the engine cylinder, the intake into such cylinder of a large fuel charge, and a forced lubrication of the piston and the bearings of the piston rod. It consists of a novel form of piston rod with co-operating means for operating it, as will be pointed out in the following specification.

In the accompanying drawings—

Figure 1 is a sectional view, somewhat diagrammatic in character, through the cylinder of an internal combustion engine, provided with my invention, taken on a plane crossing the crank shaft at right angles and showing the piston and its connections with the crank shaft in one position.

Fig. 2 is a vertical section taken on the line II—II of Fig. 3, showing the parts in a different position from Fig. 1.

Fig. 3 is a sectional view taken on a plane at right angles to that of Figs. 1 and 2 and showing the parts in the position represented in Fig. 2.

Figs. 4, 5 and 6 are transverse sectional views taken on the lines IV, V and VI, respectively, of Fig. 3.

In the accompanying drawings, 2 designates the cylinder of an internal combustion engine, and 3 the piston working therein. As the present invention is applicable to internal combustion engines of different types and constructions I have herein merely indicated it in connection with a single engine cylinder which is diagrammatically illustrated.

4 is the crank shaft. The piston rod, which is of peculiar construction, as will be described, is provided with a bearing 6 surrounding the crank portion of the shaft 4, and another bearing 7 surrounding the wrist pin 5 that unites this rod with the piston. The piston rod is formed of two separate parts, one, 9, carrying the bearing 6 and herein termed the crank shaft portion of the piston rod, and the other, 10, carrying the bearing 7 and herein termed the piston portion of the piston rod. One of these parts,

preferably the crank shaft portion, is formed with a longitudinal channel 11 in which lies the other portion, as is well represented in Fig. 4. The inner face of the piston section 60 of the piston rod is formed, on its inner face, with a longitudinal groove or channel 15, for a purpose that will be described. The bottom 13 of the channel 11 in the crank shaft portion of the piston rod, that is, the end 65 toward the bearing 6, is preferably inclined, as represented in Fig. 3; and the lower portion of this channel is closed by a cover plate 12, of a length sufficient to cover the outer or free end of the other section, 10, of the piston rod, under all working conditions. The outer end of piston rod section 10 is formed into an inclined face 14 that is adapted to fit the wall or face 13 at the bottom of the channel 11 in the crank shaft section of the 75 piston rod when the parts of the piston rod are brought into the relative positions indicated in Fig. 1. The base of the piston section, 10, of the piston rod, that is, where it joins the bearing 7, is provided with a shoulder or abutment 16 preferably having an inclined face with which a correspondingly inclined face 17 of the crank shaft portion of the piston rod comes into engagement when the parts assume the positions represented in Fig. 1. A box or enclosing casing 18 is secured to the piston rod section 10 near its base surrounding this section and covering the free end of the other piston rod section 9 under all working conditions, as represented in Figs. 3 and 6. This construction of the piston rod permits a movement of the piston relative to the crank shaft which is available of in effecting a complete scavenging of the engine cylinder and drawing thereinto 80 a large charge of the fuel mixture. When the piston is moved toward the crank shaft the free ends, 14 and 17, come simultaneously into engagement with the faces 13 and 16 which form abutments therefor, thus 85 making in effect a rigid piston rod, and the parts of the engine work under these conditions, that is, with a shortened rigid piston rod, during the compression and working strokes of the engine. On the other hand 90 when the piston is moved away from the crank shaft, as represented in Figs. 2 and 3, during scavenging and intake strokes of the piston, the parts of the piston rod slide relatively to each other, and there are spaces 95 opened between the free ends of the piston rod sections and the abutments opposite to

100

135

which they stand, as best shown in Fig. 3. As the pressures upon the piston are relatively light during these strokes it is not necessary that the piston rod be so rigid as during the compression and working strokes when the pressures are high.

I will now describe the means by which the movements of the piston relative to the crank shaft, above briefly stated, are caused to take place. 28 indicates an eccentric disk secured fast to the crank shaft alongside the journal for the bearing 6. In its inner face, that is, the face toward the piston rod, are formed two grooves, the inner, smaller, 15 of which, 29, is concentric with the crank shaft journal for the piston rod, while the larger groove, 30, is eccentric. These two grooves are so placed that they merge at the portion designated 8. The grooves are 20 separated from each other by a crescent shaped ridge 36, the ends of which are truncated, and have pivoted adjacent to them the tapering switches or gates 32, 33. The inner, concave, surface of each gate has 25 a radius corresponding with that of the outer wall of the inner groove 29, while its outer, convex, surface has a radius corresponding with the inner wall of the outer groove 30. Springs 34 act upon the heel ends of the 30 switches 32, 33 and tend to hold them in the positions to which they may be set with their outer free ends in engagement either with the inner wall of the portion 8 where the two grooves, 29 and 30, merge into one, or 35 with the outer wall, accordingly as they may be set. These walls are preferably notched, as indicated in Fig. 2, to receive the thin, free, ends of the gates. The latter when moved to engage with the inner wall of the 40 groove closes the entrances to the inner groove 29 and leave the outer groove, 30, intact, and when moved outwardly to engage the outer wall of the groove they serve to close off the outer groove and leave the inner one, 29, intact. The gate or switch 32, 45 which I term the leading one, is provided at its heel end with tangs or projections 35 adapted to extend respectively into the grooves 29 and 30; that is to say, when the 50 free end of the gate is in engagement with the outer wall of the groove the inner tang 35 extends a little way into the groove 29 so as to be engaged by an object following the path of such groove, while when the outer 55 free end of the gate engages the inner wall of the groove the outer tang extends slightly into the groove 30 and will be engaged by an object following that groove.

26 indicates a lever supported upon a fulcrum 27 carried by the bearing 6. The lever hence moves with the bearing as that is moved by the crank of the shaft 4. The lever is provided with a stud 31 adapted to lie in one of the grooves 29 or 30 and to 60 travel in one or the other thereof as the

shaft 4 turns, accordingly as the stud may be directed by the switch 32. The lever 26 extends, from its fulcrum 27, beyond the stud 31 and is connected at its free end with a link 24, the other end of which is pivotally connected, at 25, with the piston portion 10 of the piston rod, preferably near the union of such rod with its bearing 7. It will be seen by a comparison of Figs. 1 and 2 that whenever the stud 31 is in the groove 29 and travels therein, the sections of the piston are brought together, the piston rod as a whole being thus shortened, because the stud 31 is brought, by the groove 29, as close to the center of the journal of shaft 4 as it 70 is possible. It will also be seen that so long as the stud 31 lies in the groove 29 the parts will be maintained in the positions just referred to since the groove 29 is concentric with the journal with which the bearing 6 75 engages, and the lever carrying the stud 31 is pivotally supported upon such bearing. On the other hand, when the stud 31 is in the groove 30, and the disk 28 is caused to turn by the revolution of the shaft 4, the lever 26 is reciprocated and the piston moved relatively to the crank shaft, in the manner herein set forth. When the stud 31 enters the groove 30, from the merged portion 8 of the two grooves, the parts are in the position indicated in Fig. 1, and as the stud travels in the groove the lever is gradually rocked on its fulcrum until, reaching a point diametrically opposite the portion 8 of the groove, the lever has been rocked to its greatest extent, as represented in Fig. 2, and the piston moved, relatively to the crank shaft, as far as is possible with the apparatus being described. Thereafter, as the crank shaft completes its revolution the lever is reciprocated in the opposite direction moving the piston toward the crank shaft, as the stud 31 is forced inwardly toward the center of the journal of the crank shaft, through the action of the cam groove 30 as its portion 8 90 approaches the stud.

An oil channel 23 extends through the crank portion of the shaft 4 and with this channel communicates a duct 22 leading to the surface of the journal for the bearing 6. 100 A duct 19 leads from the lower end of the channel 11 in the crank shaft portion of the piston rod through the bearing 6 and terminates in a semicircular groove 37 on the inner face of the bearing, with which groove communicates the duct 22. A duct 20 leads from the face 16 through the bearing 7 to the central channel through the connecting pin 5 by which the piston is united with the piston rod. It will be seen from the foregoing description taken in connection with Fig. 3 of the drawings that there is a passage for lubricant from the crank case to the cylinder walls including the following passages: the channel 23 in the crank shaft; the ducts 22, 110 115 120 125 130

37 and 19; the space 39 between the end of the piston section of the piston rod and the abutment 13, closed by the plate 12; the channel 15; the space 40 between the outer 5 end of the crank shaft section of the piston rod, and the abutment face 16, enclosed by the box 18; the duct 20; and the channel through the wrist pin, which channel opens to the walls of the cylinder between the 10 packing rings 38 carried by the piston. The operation of the mechanism that has been described may now be stated. Starting at the beginning of the compression stroke, with the parts in the positions indicated in 15 Fig. 1, and the crank turning in the direction indicated by the arrow in that view, it will be seen that the stud 31 is about to enter the inner groove 29, being directed thereinto by the switch or gate 32. The stud 31 is 20 now as near to the center of the journal of the crank shaft as it is possible for it to be, and the lever 26 has therefore been rocked, carrying its free end toward the bearing 6. This, acting through the link 24, has moved 25 the piston toward the crank shaft and has telescoped the two portions of the piston rod until their ends, 14 and 17, respectively, engage with the abutments 13 and 16, thus shortening the piston rod and making it a 30 rigid structure from bearing 6 to bearing 7. As the crank shaft rotates, turning in the direction of the arrow, the piston which is at its extreme lowermost position, is moved upwardly by the crank, compressing the 35 charge of fuel within the cylinder. In making this compression stroke the stud 31 continues in the channel 30, and the piston is forced upwardly only so far as is permitted by the shortened piston rod. At the completion 40 of the compression stroke the fuel charge is ignited and the working stroke of the piston takes place, during which the stud 31 continues in the groove 29, maintaining the parts of the piston rod in their shortened 45 or telescoped relationship and hence in such engagement that the piston acts as a rigid connection to safely transmit to the crank shaft the force imparted to it from the piston. As the gate 32 is carried, by the rotation 50 of the crank shaft, past the stud 31 the latter acts upon the inner tang 35 at the heel of the gate to force it outwardly and rock the gate or switch and move its free end across the entrance to the inner groove 29, 55 at the same time opening the entrance to the outer groove 30 as represented in dotted lines Fig. 1. The gate being moved to this position is there maintained by the spring 34.

At the end of the outward or downward 60 stroke of the piston, completing the working stroke of the engine, the parts are again at the position indicated in Fig. 1, except that now the gate 32 stands in position to direct the stud 31 into the outer, eccentric, 65 groove 30, and the scavenging stroke of the

piston is about to begin. As the crank shaft turns raising the piston and causing the exhaust of the gases of combustion from the cylinder, the piston is simultaneously moved relative to the crank shaft journal, and away therefrom, by reason of the stud 31 moving, in the groove 30, from the position shown in Fig. 1 to that represented in Fig. 2, with the result that the piston approaches closer to the head of the cylinder on this 70 scavenging stroke than it did on the compression stroke. It follows that the gases of combustion are very completely expelled and the cylinder is thoroughly scavenged. To accomplish this the piston rod has been 80 lengthened, by the movement of the lever 26. The piston rod when lengthened is not so rigid as it is when shortened, during the compression and working strokes, but the work to be performed by the piston is not, 85 on this stroke, severe, and the parts are easily made sufficiently strong to effect the movements necessary to secure the scavenging and intake strokes. During the downward, intake, stroke of the piston it has a 90 movement jointly produced by the action of the crank shaft and of the lever 26, as will be understood, until, upon completion of the intake stroke, the parts come to the 95 positions indicated in Fig. 1 when the cycle of operations described is repeated. As the leading gate 32 is carried past the stud 31 at the commencement of the exhaust or scavenging stroke of the piston the stud acts upon the outer tang 35 shifting the gate or 100 switch to position to open the entrance to the inner groove and close that to the outer groove, putting the parts in position to effect the compression of the charge on the next reciprocation of the piston. The other or 105 following gate, 33, is shifted alternately from one position to another as it is moved, heel first, past the stud 31, and hence does not require the tangs to effect its movements. 110

I utilize the two-part piston and the movements thereof with reference to each other to effect a forced feed lubrication of the piston and the bearings of the piston rod. Whenever the piston rod is lengthened, and the two parts of the piston somewhat separated from each other, as represented in Fig. 3, there are formed spaces 39, 40, into which the lubricant is drawn from the crank case, through the channels 23, 22, 19 and 15, as already traced. These spaces are filled 115 with the lubricant, as the parts of the piston rod separate from each other, which will be forced from such spaces as the piston rod parts come together. The semicircular channels, in the journals of the crank shaft and wrist pin of the piston communicate respectively with the ducts 19 and 20 during such time only as the lubricant is being forced out from the spaces 39 and 40. When 120 these spaces are being filled the ducts 19, 130

20 are closed by the ungrooved portions of the bearings. The arrangement described insures a constant forced lubrication of the moving parts of the piston and its driving 6 connections.

It will be observed that the crank shaft 10 has a constant throw, the variable motion being given to the piston by increasing and decreasing the length of the piston rod and 15 that the mechanism by which this variable motion is imparted comprises a lever that is supported by the crank shaft portion of the piston rod and is operated by a cam device carried by the crank shaft.

15 What I claim is:—

1. In an internal combustion engine, the combination of a piston, a crank having a constant throw, an extensible piston rod connecting the crank and piston, and means 20 for lengthening the piston rod during the exhaust stroke to effect thorough scavenging of the engine cylinder.

2. In an internal combustion engine, the combination of a crank having a constant throw, a piston, an extensible piston rod connecting the crank and piston, means for lengthening the piston rod on the exhaust stroke and shortening it on the intake stroke and for maintaining it in its shortened condition 25 during the compression and working strokes.

3. In an internal combustion engine, the combination of a crank, a piston, a piston rod comprising two parts movable with reference to each other, one connected with the piston and the other with the crank shaft, a cam device carried by the crank shaft, and means carried by the piston rod and operated upon by the said cam device for 35 lengthening the piston rod during the exhaust stroke of the engine and maintaining it in shortened condition during the compression and working strokes.

4. In an internal combustion engine, the combination of a crank shaft having a constant throw, a piston, a piston rod connecting the crank shaft and piston, formed of at least two parts, one connected with the piston and the other with the crank shaft 50 and movable longitudinally relative to each other, the parts being arranged to come into engagement with each other to render the rod rigid against longitudinal strains when it is shortened, and means for lengthening the piston rod during the exhaust stroke of the engine to effect complete scavenging of the engine cylinder, and to maintain it in shortened condition during the compression and working strokes.

60 5. In an internal combustion engine, the combination of a crank, a piston, a piston rod formed of a part connected with the piston and a separate part connected with the crank shaft, these parts being movable 65 longitudinally with reference to each other,

a lever connection for moving the piston-connected part of the crank shaft relative to the other part, supported by the crank shaft part of the piston rod, and a cam device carried by the crank shaft for operating the 70 lever and causing the piston rod to be extended and the piston to move away from the crank shaft bearing during the exhaust stroke of the engine and to return toward the engine during the intake stroke and to 75 maintain it in such returned position during the compression and working strokes.

6. In an internal combustion engine, the combination of a crank shaft having a constant throw, a piston, a piston rod connecting the crank shaft and piston and formed of two parts united together but capable of telescopic movement with reference to each other, one part connected only with the piston and the other only with the crank 80 shaft, the parts being arranged so that when they are telescoped together the free end of each piston rod part has bearing against an abutment carried by the other part rendering the piston rod rigid longitudinally, and means for moving the piston-connected part of the piston rod outwardly during the exhaust stroke of the engine to effect a complete scavenging of the engine cylinder, moving it inwardly during the intake stroke and 85 maintaining it in such inward position, with the free ends of the piston rod parts against their abutments, during the compression and working strokes of the engine.

7. The combination stated in claim 6 100 when one of the parts of the piston rod is of channel construction and the other lies therein, and the free ends of the piston rod parts are beveled and engage with bevel-faced abutments.

8. In an internal combustion engine, the combination of a crank shaft having a constant throw, a piston, a piston rod formed of two separate parts, one connected with the crank shaft and the other with the piston, 110 the parts of the piston rod being united but movable longitudinally with reference to each other, a lever supported by the crank shaft portion of the piston rod and connected with the piston portion thereof for moving the latter, and a cam device fast upon the crank shaft, with which the lever engages, arranged to move the lever to cause the piston portion of the piston rod to be moved outwardly during the exhaust stroke 115 of the engine and inwardly during the intake stroke and maintained in its inward position during the compression and working strokes.

9. The combination stated in claim 8 125 when the cam device consists of a disk in which are formed two cylindrical cam grooves, one concentric with the crank shaft journal of the piston rod and the other eccentric thereto, and means for causing the 130

lever to engage with the eccentric groove during the exhaust and intake strokes and with the concentric groove during the compression and working strokes.

- 5 10. In an internal combustion engine, the combination of a crank shaft, a piston, a two-part piston rod the parts of which are movable longitudinally with reference to each other, means for causing a variable 10 movement of the piston and relative longitudinal movement of the parts of the piston rod as the piston is reciprocated by the crank shaft, and means for effecting a forced lubrication of the piston rod bearings 15 through the relative movement of the piston rod parts.

11. In an internal combustion engine, the combination of a crank shaft, a piston, a two-part piston rod, one part being con-

nected with the crank shaft and the other 20 with the piston, the parts of the piston rod being movable longitudinally with reference to each other, and the free ends of the piston rods being encased whereby when the piston part of the rod is moved relatively 25 outwardly spaces are left and enclosed by the said encasing means, the piston rod being formed with longitudinal oil ducts leading to the piston bearing and to the crank shaft bearing and communicating with the 30 said encased spaces at the ends of the piston rod sections, there being a communication between a source of oil supply and one of the said spaces, and means for causing a relative movement of the piston-connected 35 part of the piston rod as the piston is operated by the crank shaft.

MEYER NUTA.
